INVENTOR

J. H. Mac El'Rey

UNITED STATES PATENT OFFICE.

JOSEPH H. MAC EL'REY, OF PHILADELPHIA, PENNSYLVANIA.

CAR-HEATER.

SPECIFICATION forming part of Letters Patent No. 372,478, dated November 1, 1887.

Application filed March 30, 1887. Serial No. 232,981. (No model.)

To all whom it may concern:

Be it known that I, JOSEPH H. MAC EL'REY, a citizen of the United States, residing at Philadelphia, in the county of Philadelphia and State of Pennsylvania, have invented a new and useful Car-Heater, of which the following is a specification.

My invention relates to improvements in that class of car-heaters which heat the car by means of hot air issuing from suitable outlets in a pipe extending the length of the car, one or more heaters being carried by each car.

The objects of my improvements are to provide a car-heater which from its shape, material, and manner of construction cannot in cases of railroad accident be broken and spill the fire or bring any highly-heated portion of the heater in contact with the combustible material of which the car is composed, at the same time having the simplicity and ease of management of the ordinary stove or heater. I attain these objects by the apparatus illustrated in the accompanying drawings, in which--

25 Figure 1 is a front elevation with the outer ash-pit door turned back, showing the construction of the inner doors. Fig. 2 is a sectional elevation on the line *x x*, Fig. 1. Fig. 3 is a sectional plan on the line *y y*, Fig. 2. 30 Fig. 4 is an enlarged view of the door-fastening shown in Fig. 3. Fig. 5 is a sectional elevation of air-deflector and automatic valves of said deflector.

Referring to the drawings, A represents the 35 fire-pot, which is supported by the circular ribs *a* and *b*, riveted to the wrought-iron or rolled-steel plate casing B. Lugs *c c* hold the fire-pot in position in case of overturning.

The casing B is closed at the top by a 40 wrought-iron or rolled-steel plate cap C, which is connected by a neck, *d*, and collar *f* to the wrought-iron or rolled-steel plate cap E of another wrought-iron or rolled-steel plate casing, D, concentric with the inner casing, B. The 45 lower end of casing B is closed by a wrought-iron or rolled-steel plate, F, and rests on a similar plate, F', closing the end of casing D. Bolts *e e* fasten the entire apparatus to the floor of the car. (Not shown in the drawings.) The portions of the caps C and E enclosed by the neck *d* and collar *f* have perfor-

ations *g* and *g'*, allowing the products of combustion to pass into the bonnet G, and thence through the smoke pipe H to the open air, as indicated by dotted arrows. 55

Under its usual conditions--that is, when the car is in motion--the air to be heated is forced by means of a deflector, I, Fig. 5, on top of the car into the pipe J, thence to the bonnet K, and through the perforations *h h* in the cap E, into the space W between the caps C and E and the casings B and D, where it is heated by contact with the hot metal of the casing B and cap C, finally escaping through the perforations *i i* into the outlet-pipe L, and thence distributed throughout the car. The course of the air-circulation is shown by full arrows.

The double fire-doors M and M' and double ash-pit doors N and N' are identical in construction and mode of fastening, and consist of plates of wrought-iron or rolled steel filled with perforations *w w* and curved to fit the casings B or D, as the case may be. These doors slide on lugs *l* and *l'*, attached to the casings B and D, one of which and a similar one, *k* and *k'*, inverted at the top of the door, hold one end of the door in position. The other end of the door is firmly secured by the device shown in Figs. 4 and 1 as applied to the ash-pit doors. 75

As all the sliding doors are fastened in the same manner I will refer only to one. A tongue, O, projects from the casing B or D, as the case may be, holding firmly the screw-bolt P, to which is fitted the socket-nut Q, with a shoulder for receiving a socket-wrench. The end of the door is provided with a slot, *m*, to slide over the bolt P, and a recess, *m'*, which receives the end of the socket-nut Q. It will 80 be readily seen that a few turns of the nut Q in the proper direction will firmly fasten or unfasten the door, as desired. The nut Q is preferably made of such a length that when the inner door is fastened the end of the nut 85 will just clear the outer door, thus rendering it impossible for the said nut to slacken from jarring or other causes and unfasten the door. 90

A closed connection is made between the casings B and D around the fire and ash-pit doors by means of the necks *n* and *n'* and the corresponding collars *o* and *o'*. Light cast-

iron doors R and R' are hinged to frames s and s' and furnished with registers j and j' for regulating the draft.

The grate T turns eccentrically on the trunnions p p, turning in the bearings q q, and is supported in a horizontal position by the bolt U, screwing through the rib b, extending through the casings B and D, and furnished with a shoulder similar to the nut Q. Lock-nuts t t prevent the bolt from being entirely withdrawn. By withdrawing the bolt U sufficiently the grate is released, and, turning automatically on the trunnions p p, dumps the contents of the fire-pot A into the ash-pit V. The portion of casing B encircling the fire-pot A has perforations r r, to allow air circulation around the fire-pot, thus preventing overheating.

The air-deflector I, Fig. 5, consists of a short pipe with flaring ends fastened to the top and communicating with the air-supply pipe J. At each end of the deflector is a valve u and u', turning on a vertical axis set eccentrically, so that the valve opens or shuts, according as the air-current is inward or outward.

To provide a means for heating the car when stopped for any considerable length of time, a door, W', is placed on the air pipe J, and the action of the heater would be as follows: Hot air rushing up the pipe J closes the valves u and u'. Now, by opening the door W', the

heated air escapes into the car, and cold air will be supplied by the pipe L. The heater, being composed entirely of wrought-iron or rolled-steel plate three-sixteenths of an inch thick, or thereabout, except a few unimportant details, all of which might be broken away without effecting its fire-containing security, would either fully withstand any blow or crush it might receive in a railroad accident or on account of its strength and ductility would yield without fracture and still contain the fire.

I am aware that prior to my invention car-heaters have been made using the combination of a deflector, air-supply pipe, air-heating chamber and air-outlet pipe. I therefore do not claim such a combination, broadly; but,

What I do claim as my invention, and desire to secure by Letters Patent, is—

The combination, in a car-heater, of a neck, d, and collar f, a bonnet, G, and smoke-pipe H, with the caps C and E, which are provided with perforations g g, communicating with the combustion-chamber Y and forming passages 55 for the gases of combustion, substantially as described.

J. H. MAC EL'REY.
